PANTS HANGER

Filed Oct. 25, 1945

UNITED STATES PATENT OFFICE

2,418,106

PANTS HANGER

Hans J. Zimmermann, Canton, Ohio

Application October 25, 1945, Serial No. 624,386

8 Claims. (Cl. 223—95)

1

The invention relates generally to garment hangers, and more particularly to a hanger for suspending a pair of men's trousers in inverted position.

Conventional pants hangers consist of a clamp having two bars arranged to grip both trouser cuffs tightly between them, and a hook for supporting the bars. If the bars are clamped tightly enough to prevent the weight of the trousers from pulling the cuffs out of the hanger, the bars will mark the trousers, even though the bars are lined with felt or the like.

Moreover, in such hangers the bars clamp tightest in the center of the cuffs, because of the extra thicknesses of cloth at that point due to the seams, and the front and rear edges of the cuffs sometimes slip and sag, causing folds or wrinkles in the trousers.

Another disadvantage of such hangers is that they do not hold dress trousers or other cuffless trousers satisfactorily, because without the extra thickness of the cuffs, it is very difficult to clamp the trousers tightly enough to prevent them from slipping.

It is therefore an object of the present invention to provide an improved pants hanger which will hold a pair of trousers in properly creased condition without marking them in any way.

Another object is to provide an improved pants hanger which is adapted to hang trousers equally well with or without cuffs.

Another object is to provide an improved pants hanger which is adapted to be folded into a small parcel when not in use.

A further object is to provide an improved pants hanger which is longitudinally adjustable for fitting trousers of a variety of widths.

Finally, it is an object of the present invention to provide an improved pants hanger which overcomes all the disadvantages of conventional hangers, which is inexpensive to manufacture, easy to use, and attractive in appearance.

These and other objects and advantages apparent from the following description and claims, may be obtained and the described difficulties overcome by the devices, constructions, combinations and parts which comprise the present invention, the nature of which is set forth in the following general statement, and a preferred embodiment of which is set forth by way of example in the following description and shown in the drawings, and which is particularly and distinctly pointed out and set forth in the appended claims forming part hereof.

2

The nature of the improvements of the present invention may be stated in general terms as including a pair of inner tubes slideable in an outer tube and urged expansively outward in opposite directions by spring means within the inner tubes, there being foldable loops depending from the ends of said tubes for frictionally engaging the insides of a pair of trouser cuffs at the creases thereof, said loops being normally locked on said inner tubes in depending position, and a hook having its lower end extending through said outer tube and engaging slots in said inner tubes for limiting outward expanding movement thereof.

A preferred embodiment of the improved pants hanger is shown by way of example in the accompanying drawings, in which:

Figure 1 is a side elevation of the improved hanger, showing one of the pants engaging loops in depending position and one in folded position;

Fig. 2 is an end view thereof;

Fig. 3 is a view similar to Fig. 1 with parts broken away and in section to show the internal construction;

Fig. 4 is a transverse sectional view as on line 4—4, Fig. 2;

Fig. 5 is a longitudinal sectional view as on line 5—5, Fig. 2;

Fig. 6 is a fragmentary isometric view showing a pair of trousers supported by the improved hanger; and

Fig. 7 is a perspective view of one of the inner tubes.

Similar numerals refer to similar parts throughout the several views of the drawings.

The improved hanger preferably includes an outer tube 1 which may be provided at its central portion with diametrically opposite holes 8 for receiving the lower inturned ends 9 of a hook 10, as best shown in Figs. 4 and 5. The hook 10 may conveniently be made of a single piece of wire having a loop 10a at its outer end, as shown in Figs. 2 and 6, and is adapted to engage over a hanger bar or the like in a clothes closet.

Within the outer tube 1 is a pair of inner tubes 11 and 12 which are freely slideable in the tube 1, and which have means secured on their outer ends for frictionally engaging inside the bottom ends of a pair of trousers. Each engaging means is preferably a double loop having inner legs 13 terminating in angular end portions 14 which extend toward each other through diametrically opposite holes 15 in the end portions of the tubes 11 and 12. The end portions 14 extend far enough into the tubes 11 and 12 to form abut-

ments for the ends of helical springs 16, which are located within the tubes 11 and 12 and act to urge the tubes outwardly away from each other.

The inner legs 13 of the double loops depend downwardly at opposite sides of the tubes 11 and 12 and are looped or bent forwardly and upwardly at 17 to form outer legs 18, the upper ends of which are joined in upper loops 19 which fit tightly over the outer ends of the tubes 11 and 12. The legs 18 may be serrated as indicated at 20 for frictionally engaging the insides of a pair of trousers T in the manner indicated in Fig. 6, and the upper loops 19 normally abut the upper ends of the tubes 11 and 12 so as to lock the double loops in trouser engaging position. However, when it is desired to fold the hanger, the loops may be folded inwardly along side the tubes as indicated in Fig. 1, by first springing the loops 19 outwardly.

Thus, the inner tubes 11 and 12 are longitudinally adjustable in the outer tube 7, and the springs 16 urge the inner tubes away from each other so as to exert an outward pressure on the legs 18 when engaging trousers of a variety of widths.

As indicated in Figs. 3 and 5, the inner end portions of the tubes 11 and 12 are cut away by slitting the tubes longitudinally, and the cut away portion of each tube is adapted to fit the remaining portion of the other tube, when the tubes 11 and 12 are interfitted as shown in the drawings. In other words, the half cylindrical end portion 21 of the tube 11 fits within the cut out portion 22 of tube 12, and the half cylindrical portion 23 of tube 12 fits within the cut out portion 24 of tube 11, so that the overlapping parts of the tube form a cylinder.

Each half cylindrical portion 21 and 23 is provided with a longitudinally extending slot 25 into which are received the ends 9 of the hook 10, so that engagement of the ends 9 with the ends of the slots 25 will limit the outward movement of the tubes 11 and 12 and prevent the hanger from coming apart. The particular construction of the tubes 11 and 12 including the half cylindrical portions 21 and 23 with their slots 25, provides for making the tubes 11 and 12 identical, which reduces the cost of manufacture materially.

It will be understood that the relative positions of the tubes in Figs. 1, 3 and 5 are those normally occupied when the hanger is supporting a pair of trousers as in Fig. 6, wherein the outer legs 18 of the double loops are engaging the insides of the trouser cuffs.

In the operation of the improved hanger, assuming that the double loops are in the depending position of Fig. 3, all that is necessary is to force the tubes 11 and 12 inwardly against springs 16 until they can be inserted inside the trouser cuffs in the manner shown in Fig. 6, whereupon the inward pressure on the tubes is released and the springs 16 urge the serrated edges 19 outwardly into frictional engagement with the cloth of the trousers in the fold lines thereof.

Thus, there is no clamping bar pressing on the outside of the trouser cuffs to mark the same, and the frictional engagement of the legs 18 is such as to support dress trousers or trousers without cuffs equally well. The action of the springs 16 is such as to support the trousers without permitting sagging thereof in any way, as in the case of the conventional clamp hangers now in use.

When it is desired to fold the improved hanger, the upper loop 19 of the engaging members are sprung outwardly to permit folding the loops in-

wardly as shown in Fig. 1, and the hook loop 10 may be swung to the right as viewed in Fig. 1, to fold closely alongside the outer tube 7.

In the improved hanger construction, the provision of two springs 16 abutting the end portions 14 of the engaging means at the outer ends of the springs and abutting the ends 9 of the hook 10 at the inner ends of the springs results in centering the outer tube 7 with respect to the inner tubes 11 regardless of the adjusted position of the inner tubes. This arrangement not only presents an attractive appearance but maintains the hook 10 centered with respect to the hanger so that pants or the like suspended from the hanger always hang straight downwardly from a bar or the like on which the hanger is engaged.

Moreover, the improved hanger construction has a very simplified design consisting of an outer tube, two identical inner tubes, a hook member, two identical springs, and two identical trousers engaging members which are easy to assemble without any rivets, screws, or other special securing means; and the component parts 25 may be made without welding or the like.

Due to the absence of welding or riveting, no special finishing operations are required and there are no projections on the hanger to catch or tear clothes. Moreover, although the parts 30 can be made of metal, due to the absence of special fastening means, one or more of the parts may be made of plastic material.

Finally, the tubular construction of the inner and outer tubes forms a stiff and strong hanger; 35 and the construction and mounting of the trousers engaging means also provides a stiff and strong arrangement.

Thus, the improved hanger overcomes the disadvantages of conventional hangers, is inexpensive to manufacture, easy to use, and attractive in appearance.

In the foregoing description, certain terms have been used for the sake of clarity, but no unnecessary limitations are to be implied therefrom 45 beyond the requirements of the prior art, because such words are used for descriptive purposes and are intended to be broadly construed.

Moreover, the embodiments of the improved construction shown and described are by way 50 of example, and the scope of the present invention is not limited to the exact details of construction of the various parts.

Having now described the features of the invention, the construction, operation and use of 55 a preferred embodiment thereof, and the new and useful advantageous results obtained thereby; the novel and improved constructions and arrangements, and reasonable mechanical equivalents thereof which are obvious to those skilled 60 in the art, are set forth in the appended claims.

I claim:

1. Pants hanger construction including an outer tube, a pair of inner tubes slideable longitudinally therein, foldable loops depending from the outer ends of said inner tubes for engaging the insides of a pair of trousers, spring means within said inner tubes urging them longitudinally outwardly away from each other, means at the upper ends of said loops normally abutting the inner tubes to lock the loops in depending position, and a hook having lower end portions extending through said outer tube and means upon the inner tubes cooperating with said lower end portion of the hook for limiting longitudinal movement of the inner tubes.

2. Pants hanger construction including an outer tube, a pair of inner tubes slideable longitudinally therein, foldable loops depending from the outer ends of said inner tubes for engaging the insides of a pair of trousers, the inner end portions of said inner tubes being half-cylindrical and overlapping each other to form a cylinder, said half-cylindrical portions having diametrically opposite longitudinal slots therein, helical springs within said inner tubes urging them longitudinally outwardly away from each other, means at the upper ends of said loops normally abutting the inner tubes to lock the loops in depending position, and a hook having lower end portions extending through said outer tube and entered in said slots in said inner tubes for limiting longitudinal movement thereof.

3. Pants hanger construction including an outer tube, a pair of inner tubes slideable longitudinally therein, foldable loops depending from the outer ends of said inner tubes for engaging the insides of a pair of trousers, said loops having end portions extending into said inner tubes, helical springs interposed between the loop end portions urging said inner tubes longitudinally outwardly away from each other, said loops having upper portions normally engaging over the upper sides of said inner tubes for locking the loops in depending position, and a hook for supporting said outer tube.

4. Pants hanger construction including an outer tube, a pair of inner tubes slideable longitudinally therein, spring means urging said inner tubes apart, a pants engaging member at the outer end of each inner tube, the inner end portions of said inner tubes being half-cylindrical and overlapping each other to form a cylinder, said half-cylindrical portions having diametrically opposite longitudinal slots therein, and a hanger hook having angular ends extending through said outer tube and into said slots for limiting longitudinal movement of said inner tubes.

5. Pants hanger construction including an outer tube, a pair of inner tubes slideable longitudinally therein, spring means urging said inner tubes apart, a double loop depending from the outer ends of said inner tubes, each double loop including a trouser-engaging front leg and a rear leg at each side of said inner tube, said front legs being connected together by an upper loop portion normally fitting over said inner tube for locking the legs in depending position, and said rear legs having angular ends extending through said inner tubes for pivotally mounting the double loops on the tubes and forming abutments for the outer ends of said spring means.

6. Pants hanger construction including an outer tube, a pair of inner tubes slideable longitudinally therein, spring means urging said inner

tubes apart, a double loop depending from the outer ends of said inner tubes, each double loop including a trouser-engaging front leg and a rear leg at each side of said inner tube, said front legs being connected together by an upper loop portion normally fitting over said inner tube for locking the legs in depending position, and said rear legs having angular ends extending through said inner tubes for pivotally mounting the double loops on the tubes and forming abutments for the outer ends of said spring means, the inner end portions of said inner tubes being half-cylindrical and overlapping each other to form a cylinder, said half-cylindrical portions having diametrically opposite longitudinal slots therein, and a hanger hook having angular ends extending through said outer tube and into said slots for limiting longitudinal movement of said inner tubes and forming an abutment for the inner ends of said spring means.

7. Pants hanger construction including an outer tube, a pair of inner tubes slideable longitudinally therein, foldable loops depending from the outer ends of said inner tubes for engaging the insides of a pair of trousers, spring means within said inner tubes urging them longitudinally outwardly away from each other, means at the upper ends of said loops normally engaging over the upper sides of the inner tubes to lock the loops in depending position, a hook having lower end portions extending through said outer tube and means upon the inner tubes cooperating with said lower end portions of the hook for limiting longitudinal movement of the inner tubes.

8. Pants hanger construction including an outer tube, a pair of inner tubes slideable longitudinally therein, foldable loops depending from the outer ends of said inner tubes for engaging the insides of a pair of trousers, said loops having end portions extending into said inner tubes, helical springs interposed between the loop end portions urging said inner tubes longitudinally outwardly away from each other, said loops having upper portions normally abutting said inner tubes for locking the loops in depending position, a hook for supporting said outer loop and cooperating means upon the hook and the inner tubes for limiting longitudinal movement of the inner tubes.
